J. KAUFMAN

CONTAINER

Filed Feb. 19, 1925

INVENTOR
Joseph Kaufman
BY William S. Blatt
ATTORNEY

UNITED STATES PATENT OFFICE.

JOSEPH KAUFMAN, OF BRONXVILLE, NEW YORK, ASSIGNOR TO AMERICAN SAFETY RAZOR CORPORATION, OF NEW YORK, N. Y., A CORPORATION OF VIRGINIA.

CONTAINER.

Application filed February 19, 1925. Serial No. 10,193.

My present invention relates generally to containers and to their association and co-ordinately to such an association of containers as will on the one hand suggest and drive home effectively the advertising and selling features of the article contained in one of them, and as will on the other hand give to the user of the article a physical evidence of the benefits resulting from its use.

10 As is well known, the development of self-shaving is more or less tied up with the development of what is known as the safety razor, of which there are numerous types on the market.

15 While the factors of convenience and cleanliness have had a great deal to do with the almost universal practice of men to shave themselves, the greatest factor that has resulted in its universal development, and 20 which factor has become of the greatest importance, is the saving resulting, particularly in view of the fact that the cost of shaving in establishments known as barber shops, has increased with the general rise in 25 the cost of all commodities and of service.

In order to bring home this factor of saving and consequently to increase the use of safety razors and their sale, slogans such as "Shave and save" have been adopted to put 30 in as pithy and as attractive a way the fact that by shaving oneself with an outfit, the initial cost of which is relatively small and the upkeep of which is also correspondingly small, a relatively large saving can be effected.

35 It is obvious that slogans such as "Shave and save" have been presented to the individual hitherto by advertisements of various characters, which, however, do not generally bring home the effect thereof at the time desired, namely, just at the time when the user is actually shaving.

40 One of the objects of my invention is to form a razor case container of such a character that the slogan "Shave and save" or its import, will be forcibly presented to the user of a razor contained in such case every time the individual uses such razor.

45 Thrift campaigns, that is, campaigns for the accumulation of savings have been carried on extensively, particularly by the savings institutions and banks and in further-

ance of this campaign, the practice has grown up among the savings banks to distribute small coin containers or boxes in 55 which coins can be dropped and from which the coins are to be removed by an official of the bank and accepted as a deposit in that bank.

One of the objects of my invention is to 60 combine the savings idea as carried on by the distribution of coin containers and the thrift idea as represented by the savings and service when a man shaves himself, so that a definite meaning is given to the savings so accumulated, so that such savings 65 will represent not merely money laid aside and accumulated, but actual economies on the part of the person so saving.

Where I have attempted to attain this result by associating together a razor container and a coin box in such a way that they form an integral structure, I find that this arrangement is open to the inconvenience that where, on the one hand, the user handles 70 the shaving outfit, he must at the same time handle the coin container and where, on the other hand, he takes the coin container to the bank for the removal and the deposit of the money, he must take the shaving set 80 along.

Another object of my invention therefore is the provision of an arrangement whereby in an arrangement such as that set forth in 85 which there is associated a container for an implement such as a razor, as a result of which economies are effected, and a coin container in which the money saved by such economies can be deposited, that the two can 90 be disassociated at will and each be complete in itself so that the containers can be used independently of each other and the two can be separated at will without in any way effecting the completeness of either.

95 My invention generally involves the provision of a new, useful, simple and economically constructed and effective container made up of separable containing portions and so associated that they can be associated or disassociated at will without impairing 100 the effectiveness of each as a complete container, and more particularly a composite container of a character in which the subsidiary containers bear such relationship to

each other, that the money saved by the economies effected by one can be accumulated in the other.

For the attainment of these objects and such other objects as may hereinafter appear or be pointed out, I have illustrated embodiments of my invention in the drawings, wherein:

Fig. 1 is a perspective view of my composite container;

Fig. 2 is a transverse vertical section through the container of Fig. 1 at line 2—2 thereof;

Fig. 3 is a vertical section taken on line 3—3 of Fig. 2;

Fig. 4 is a perspective view of the upper half or the coin holding part thereof looking at the bottom;

Fig. 5 is a perspective view of the shaving outfit container part thereof;

Fig. 6 is a view of a modified embodiment of the shaving outfit container part; and

Fig. 7 is a perspective view of a separable cover to be employed for the shaving outfit container part.

Before describing the details of the illustrated embodiments, I will premise that the composite container of Fig. 1 is formed by associating together the coin container 10 of Fig. 4 and the shaving outfit container 11 of Fig. 5.

The coin container 10 is formed of any preferred or desired material such as sheet metal and is given any preferred or desired contour and is provided preferably on its upper surface with the slot 12 through which the coins are to be deposited and with the closed bottom 13 having an opening 40 therein closed preferably by the removable member 14 released from its locked closing position by a key to be inserted in the key hole 15.

Where desired, the arrangement can be such that the key to be inserted in the key hole 15 for the release of the bottom closure member 14 may be of a character that it is in possession only of an officer of a bank so that coins deposited in the container 10 can be removed therefrom only by an officer of a bank on the premises of the bank and for purposes of deposit to a savings account only.

The shaving outfit container 11 may also be made of any desired or preferred material such as sheet metal as by a stamping operation and has its interior sectioned off for receiving parts of the razor outfit and also blades or blade holders as more clearly shown in connection with the embodiments of Fig. 6. The shaving outfit container of Fig. 5 may be provided with a top closure member 16 which, as shown in the drawings, is hinged at 17. The container 11 is of such contour and dimensions with refer-

ence to the coin container 10 that the two, when associated together in superimposed position, as shown in Fig. 1, form what is substantially a composite container, the upper or coin container having the appearance 70 of the cover of the composite container and the container 11 having the appearance of the body or base member thereof.

For the purpose of permitting these two containers to be associated together and to be 75 so maintained as long as desired, and yet permit of their complete separation and independent use without impairing the full effectiveness of either, I show in the embodiment illustrated, the coin container provided with a continuous flange depending therefrom (see Fig. 4), this flange having on the inner surface of its rear wall 20 the forwardly projecting pins 21, the number of which may be as desired, or found convenient, and on its front wall 22 the locking button 23. There is thus provided in the lower end of the container a space below the bottom 13, which not only provides space for the bottom closure 14 and for this 90 bottom closure being hidden from view when the container is used by itself, but also permits of the association referred to and for this purpose, the razor outfit container 11 is provided along its rear wall with the 95 upwardly projecting flanges 25, provided with holes 26, the flanges being preferably equal in number to the pins 21 provided on the inner surface of the rear wall 20 of the flange, and the holes 26 being of a size to 100 easily receive these pins. The shaving outfit container 11 is further provided on its front wall with the upwardly projecting spring lock member 27 arranged to cooperate with the locking pin 23 provided on the 105 front wall 22 of the flange.

The manner of assembling the coin container of Fig. 4 with the shaving outfit container of Fig. 5 so as to give a composite container of Fig. 1, merely involves 110 therefore the positioning of the pins 21 of the coin container within the openings 26 in the flanges 25 on the shaving outfit container 11 and the engagement of the locking members 23 and 27. The openings 26 of the 115 flanges 25 are made sufficiently larger than the pins so as to allow of a pivotal movement between the two so that when the locking spring 27 is pushed inwardly by pressure upon the projecting member 28, this 120 spring 27 will be moved inwardly sufficiently so as to disengage the opening 29 from the pin 23 of the coin container to permit of a sufficient movement of the container 11 relatively to the container 10, so that the two 125 can be separated.

In Fig. 6 of the drawing, I show a modified form in which no cover is provided for the shaving outfit container, whereby the parts of the shaving outfit contained therein 130

can be of such a size as to project above the top thereof to that extent to which that excess can be accommodated within the space formed below the bottom 13 of the coin container in Fig. 4, and in Fig. 7 of the drawing I show the cover member 30 which can serve as a cover for the embodiment of Fig. 6 and which is for this reason made separable therefrom and this cover, for this purpose, is provided with the continuous flange 31, the rear walls of which are provided on its inner surface with the forwardly and inwardly projecting pins 32 and on its forward wall with the inwardly projecting pin 15 23, which pins 32 and 23 cooperate with the openings 26 and 29 in the flanges 25 and the spring lock 27 formed in the shaving outfit container of Fig. 6 in the same way as do the corresponding elements in the coin 20 box bottom of Fig. 4 so that, in effect, in these embodiments of this invention, the coin box container of Fig. 4 and the cover member 30 of Fig. 7 form alternative closures for the shaving outfit container of Fig. 25 6 so that where it is desired to have the composite construction of Fig. 1, the coin box can be associated with the safety razor outfit containers of either Figs. 5 or 6, or where it is desired to disassociate the two, the cover 30 member 30 of Fig. 7 can be associated with the safety razor outfit container of Fig. 6.

It will be understood that where desired, the cover member of Fig. 7 can equally well be associated with the razor outfit container 35 of Fig. 5 in the same way as has been described in connection with the outfit container of Fig. 6.

The cover container 30 where employed may be provided with the reflector or mirror 40 34 positioned as shown in Fig. 7 and received beneath the flange 35.

It will be understood from the description thus far given, that I have provided a composite container which serves as a powerful 45 argument for saving and can be distributed by savings institutions with considerable success because of the fact that not only is there something of practical value associated with the container, but the object of practical 50 value is of such a character that its use effects economy of money, which can be accumulated in the coin container so that a person should have every incentive to accumulate such money in the coin container as he saves by shaving himself, as that represents a very definite economy and that as a result of the habit so formed, the thrift campaign will be materially advanced. At the same time, by the arrangement set forth, 55 the containers are so associated that they can be disassociated at will and used independently of each other at will and as complete receptacles and without in any way reducing the effectiveness of either.

Having thus described my invention and 65 illustrated its use, what I claim as new and desire to secure by Letters Patent is—

1. In a device of the character described, in combination, a container adapted to receive an article, the use of which serves to 70 economize in expense such as a shaving implement, and a coin container, the containers each being complete in themselves and capable of independent use and means for 75 separably associating said containers so that they form a composite multi-container construction, with the containers in superimposed relation, the walls of the upper container extending below the bottom thereof, said aforementioned means including a 80 member projecting from said extending portion of the walls.

2. In a device of the character described, in combination, a container adapted to receive an article, the use of which serves to 85 economize in expense such as a shaving implement, and a coin container, the containers each being complete in themselves and capable of independent use and means for 90 separably associating said containers so that they form a composite multi-container construction, with the containers in superimposed relation, the walls of the upper container extending below the bottom thereof, said aforementioned means including a 95 member projecting from said extending portion of the walls, and a member extending upwardly from the lower compartment.

3. In a device of the character described, in combination, a container adapted to receive an article, the use of which serves to 100 economize in expense such as a shaving implement, and a coin container, the containers each being complete in themselves and capable of independent use and means for 105 separably associating said containers so that they form a composite multi-container construction, with the containers in superimposed relation, the walls of the upper container extending below the bottom thereof, said aforementioned means including a 110 member projecting from said extending portion of the walls, and a closure carried by the upper end of said lower container.

4. In a device of the character described, in combination, a container adapted to receive an article, the use of which serves to 115 economize in expense such as a shaving implement, and a coin container, the containers each being complete in themselves and capable of independent use and means for 120 separably associating said containers so that they form a composite multi-container construction, with the containers in superimposed relation, the walls of the upper container extending below the bottom thereof, said aforementioned means including members 125 projecting from opposite portions of

said extending portions of the walls, for providing a separable pivot for the containers and a lock therefor.

5. In a device of the character described, in combination, a shaving outfit container, a closure therefor, a coin container arranged and adapted to be associated therewith in superimposed relation, whereby said coin container simulates and forms a cover for

said razor outfit container, the coin container being provided in its bottom with an opening and a closure therefor, whereby said closure will be hidden from view when the two containers are in associated relation.

10
15 In witness whereof, I have hereunto signed my name.

JOSEPH KAUFMAN.
